COMPARTMENT COMB

William J. Martino, Garden City, Mich.

Application June 15, 1950, Serial No. 168,197

6 Claims. (Cl. 132—79)

1

The present invention relates to a compartment comb having a hollow container particularly adapted to contain hairpins or other small articles, and wherein such container is pivotally attached to the body of the comb and is adapted to swing out of alignment with the body of the comb when access to the container is desired.

Many compartment comb constructions have been developed, but most of the constructions utilize compartments having sliding covers. These compartments usually render the back of the comb bulky. Further, sliding of the covers within the necessary track portions has been found difficult and if the cover and track are not made with precision, sticking often results. In addition, the constructions are often expensive to manufacture, and hence, many of the patented constructions have never been manufactured.

Therefore, a primary object of the present invention is to provide an improved compartment comb of simplified and economical construction wherein a container is provided which aligns with the body of the comb in the closed position and is adapted to be swung at an angle to the body of the comb on a pivotal connection therewith when access to the container is desired.

Another object of the present invention is to provide such a compartment comb wherein the container is shaped to fit into the contour of the body of the comb in the closed position, thus avoiding entangling the hair during combing and providing an integral body portion free of protrusions and objectionable flanges, covers and the like.

Another object of the present invention is to provide such a compartment comb wherein the container and comb are molded separately of plastic, the plastic body portion of the comb being readily sprung so that the container may be snapped into place.

It is another object of the present invention to provide such a construction wherein a simple locking device is provided as an integral part of the receptacle and comb body.

It is a further object of the present invention to provide a compartment comb including a container which is disposed within the comb body and is movable relative thereto to provide access to the interior of the container.

Other objects of this invention will appear in the following description and appended claims, reference being had to the accompanying drawings forming a part of this specification wherein like reference characters designate corresponding parts in the several views.

2

In the drawings:

Fig. 1 is a side elevation of a compartment comb embodying the present invention, with a portion of the container being broken away to reveal the internal construction.

Fig. 2 is a plan view of the comb shown in Fig. 1, with the open positions of the container shown in phantom.

Fig. 3 is a sectional elevation taken along the line 3—3 in the direction of the arrows, in Fig. 1.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, a comb preferably formed of plastic, is shown having a body 10 and teeth 11 affixed thereto. The body 10 is provided with an elongated opening 12 extending transversely therethrough. At substantially the middle point of the opening 12, an internal upper seat 13 and an internal lower seat 14 are provided. Near one end of the opening 12, a recess 15 is provided.

A container 16 is formed separate from said comb and is preferably molded of plastic. The container is preferably rectangular in cross section with rounded corners. However, other configurations may be used without departing from the spirit of my invention. The container is hollow and is open on one end so that bobby pins and other small articles may be stored therein.

An upper pin 17 and a lower pin 18 are formed on the top and bottom of the receptacle 16, respectively, and are vertically aligned. A lug 19 is formed near one end of the container 16 and is adapted to mate with the recess 15 formed in the body 10 of the comb.

As previously stated, the comb and container are preferably formed of plastic and can be made of separate colors, if desired, to give a unique and attractive appearance to the entire compartment comb. The device is assembled by aligning the container 16 with the opening 12 in the comb and then exerting a force against the container 16. The pins 17 and 18 will spring the plastic body portion adjacent the opening 12 out of the way until the pins 17 and 18 locate in the internal seats 13 and 14. At this point, the plastic body portion adjacent the opening

12 will spring back into position and the comb is ready for use.

The recess 15 in the back 10 of the comb provides a tight fit with the lug 19 on the container 16 so that the container is locked in the closed position against accidental pivoting. When it is desired to remove articles from the inside of the container, the container 16 is pressed along one side or the other near one of the ends and the container will pivot to the dotted line positions shown in Fig. 2 of the drawings.

From the above description, it will be seen that I have provided a simple and efficient compartment comb which is formed of only two parts. This construction is readily adaptable to mass production at low cost so that the comb may be marketed at a low price. The construction provides an integral attractive design and permits a two tone appearance, if desired. Further, the construction is not only simple to manufacture, but is also extremely simple to assemble.

Having thus described my invention, I claim:

1. In a compartment comb, the combination of a body portion therein having an elongated transverse opening therethrough, a hollow container having an open end pivotally disposed within said transverse opening, said container being adapted to align with the body portion in the closed position and being adapted to move about its pivot axis to an angle transverse to the longitudinal axis of the body in the open position, thus providing access to the open end of the container in the open position.

2. A compartment comb as claimed in claim 1 and further characterized in that the pivot axis is located substantially in the center of said container.

3. A compartment comb as claimed in claim 1 and further characterized in that locking means are provided to hold said container within the opening in said comb body in the closed position.

4. A compartment comb as claimed in claim 3 and further characterized in that the locking means comprise a lug formed near one end of said container which is adapted to seat in a recess in said comb body.

5. A compartment comb as claimed in claim 1 and further characterized in that said container is shaped to conform to the contour of the comb body so that an integral body portion is provided when the container is in the closed position.

15 6. A compartment comb comprising a comb body having an elongated transverse opening therethrough, the body of said comb contiguous to the top and the bottom of said opening being provided with vertically aligned seats and a portion of said comb body contiguous to the opening also being provided with a recess, a container of a configuration which blends with the 20 contour of the comb body in the closed position and having a pin extending at opposed points from the top and bottom of said container, said pins being adapted to seat in the seats provided in said comb body, said container also having a lug extending therefrom which is adapted to mate with the recess in said comb body to provide a locking means.

25 WILLIAM J. MARTINO.
